Primary Examiner — Rosemary K Tarcza*Assistant Examiner* — Leah E Hoeferkamp(74) *Attorney, Agent, or Firm* — Sughrue Mion, PLLC(57) **CLAIM**

The ornamental design for a connector as shown and described.

DESCRIPTION

1. Connector

1.1: Top view

1.2: Front perspective view

1.3: Rear perspective view

1.4: Front view

1.5: Side view

1.6: Rear view

1.7: Bottom view

1.8: Side view

The hatchings in the representation represent contours only and do not illustrate an ornamentation or decoration on the surface of the product.

1 Claim, 8 Drawing Sheets(56)
